UNITED STATES PATENT OFFICE.

EDWARD W. LAWSON, OF WEST PALM BEACH, FLORIDA.

DESIGN FOR A SHOVEL.

Application filed May 16, 1928. Serial No. 26,692. Term of patent 7 years.

To all whom it may concern:

Be it known that I, EDWARD W. LAWSON, a citizen of the United States, residing at West Palm Beach, in the county of Palm Beach, and State of Florida, have invented a new, original, and ornamental Design for a Shovel, of which the following is a specification, reference being had to the accompanying drawing, forming part thereof.

Fig. 1 is a perspective view taken from the front, showing my new design,

Fig. 2 is a front end elevation of the shovel, showing my new design.

I claim:

The ornamental design for a shovel, as shown.

EDWARD W. LAWSON.
